(57) **CLAIM**

The ornamental design for a lid for a microwaveable container, as shown and described.

DESCRIPTION

This application is related to co-pending Ser. Nos. 29/572, 669 and 15/223,132 which are incorporated herein by reference.

FIG. 1 is a top, front and right side perspective view of a lid for a microwaveable container showing our new design; FIG. 2 is a bottom, front and right side perspective view thereof;

FIG. 3 is a right side elevation view, the left side elevation being identical thereto;

FIG. 4 is a front elevation view, the rear elevation being identical thereto;

FIG. 5 is a top plan view thereof;

FIG. 6 is a bottom plan view thereof; and,

FIG. 7 is a cross-sectional view taken along line 7-7 of FIG. 5.
